UNITED STATES PATENT OFFICE.

FRANCOIS CHIPAULT, OF NEW YORK, N. Y., ASSIGNOR TO JAY L. WOLF,
OF NEW YORK, N. Y.

SELF-LIGHTING ATTACHMENT FOR GAS-BURNERS.

No. 838,239.

Specification of Letters Patent.

Patented Dec. 11, 1906.

Application filed June 26, 1906. Serial No. 323,477.

To all whom it may concern:

Be it known that I, FRANCOIS CHIPAULT, a citizen of France, residing at New York, in the county and State of New York, have invented certain new and useful Improvements in Self-Lighting Attachments for Gas-Burners, of which the following is a specification, reference being had to the drawings accompanying and forming part of the same.

My invention relates to self-lighting attachments for gas-burners, and has for its chief object to provide an effective and durable device of the character which shall be simple in construction and readily applicable to existing burners with but slight if any modification of the latter.

To this and other ends the invention consists in the novel features of construction, arrangements of parts, and combinations of elements hereinafter described, and more particularly set forth in the appended claims.

In the annexed drawings I have illustrated the preferred form of my invention, where-

Figure 1 is a side elevation, partly in section, of an incandescent gas-burner with my attachment applied to it. Fig. 2 is a detail side view at right angles to that of Fig. 1, showing the valve-actuating device. Fig. 3 is a detail sectional view of the device for igniting the pilot-light. Fig. 4 is a detail sectional view of the pilot-valve and connections. Figs. 5, 6, 7, and 8 are sectional views on line V V of Fig. 4, showing the four different positions of the pilot-valve.

Referring now more particularly to Fig. 1, A indicates an incandescent gas-burner of any convenient type, having a Bunsen or mixing tube *a* leading to a burner-cap *a'*, over which is suspended the mantle. (Not shown.) The lower end *a*² of the mixing-tube is internally threaded, as is customarily done for the purpose of attachment to the threaded end of a pipe or fixture conveying gas. In the present case, however, the burner is screwed on the threaded nipple *b* of a valve member B, Figs. 1 and 4. The latter is preferably of cylindrical form and has in its lower portion an upwardly-tapering or conical opening or socket *b'* for a correspondingly-tapered plug or seat *B'*. The latter is hollow, as shown in Fig. 4, and is internally threaded at its orifice so as to be screwed on the gas-fixture.

The member B is provided with a gas-passage *b*², extending from the side of the socket *b'* to the longitudinal passage in the nipple *b*, and in the side of the tapered seat *B'* in the same horizontal plane as the inlet of the passage *b*² is an aperture *b*³. It will therefore be seen that by turning the cylindrical valve member B the passage *b*² therein can be thrown into or out of register with the aperture *b*³, thereby opening or closing the supply of gas to the burner.

Through the side of the valve member B opposite to the passage *b*², but somewhat less than one hundred and eighty degrees therefrom, is an aperture *b*⁴, adapted to receive the threaded neck *c* of a support C for a pilot-tube. For convenience of illustration the aperture *b*⁴ in Fig. 4 is shown diametrically opposite to the passage *b*². The support C has an opening in its upper side to receive the lower end of the pilot-tube and its neck *c* is provided with a longitudinal passage *b*⁵ in communication with the aperture in which the neck is secured. Diametrically opposite the main burner-port *b*³ in the conical seating member *B'* is a pilot-port *b*⁶, adapted to register with the adjacent orifice of the aperture *b*⁴ when the valve member *B'* is rotated to the proper extent. The parts B and *B'* may be conveniently secured together by a screw *s*, extending through the top of the seat *B'*, as shown clearly in Fig. 4.

The position of the parts when the burner is not in use is shown in Fig. 5. Therein it will be seen that the valve member B occupies a position in which neither the passage *b*² nor the aperture *b*⁴ is in register with the adjacent port in the conical seat. If now the outer member B be turned in the direction of the arrow in Fig. 5 to the position shown in Fig. 6, the aperture *b*⁴ will be brought into register with the pilot-port *b*⁶ and gas will flow into the pilot-support and thence to the pilot-burner, hereinafter described, while the passage *b*² will be carried beyond the main burner-port *b*³. If now the rotary valve member be turned backward, or counter-clockwise, to the position of Fig. 7, the passage *b*² will be brought into partial register with the main burner-port *b*³ and gas will flow to the mixing-tube, while the pilot-aperture *b*⁶ will be in partial register with the pilot-port. The means whereby these movements effect the ignition of the burner will now be described.

The pilot-tube P extends into the support C and preferably fits loosely enough therein to be readily withdrawn when desirable for any purpose, as cleaning, or repair, &c. 5 The tube extends through the bottom of the chimney-gallery G, Fig. 1, and is provided with a flat rectangular block R, provided with a longitudinal passage r, communicating with a transverse passage r' and a second 10 longitudinal passage r'', communicating with the latter. Above the block, which preferably rests on the bottom of the chimney-gallery, the pilot-tube extends from the passage r into proximity to the mantle, so that 15 the pilot-flame will ignite the gas issuing from the main burner. On the top of the block R, in communication with the passage r'' and alongside of the pilot-tube, is a small auxiliary pilot-burner p, and extending above 20 the latter, supported on standards p' p', are buttons of catalytic material p², arranged so that gas issuing from the auxiliary pilot-burner will strike them and be ignited. Depending from the catalytic bodies are the 25 usual platinum wires p³.

It will now be seen that when the valve is turned to the position of Fig. 6 the gas passing through the pilot-port b⁶ and into the lower end of the pilot-tube will flow into 30 block R, and issuing in a fine stream against the igniters p² will be ignited thereby, the flame extending from the auxiliary pilot to a point adjacent to the upper end of the pilot-tube. At the same time gas flows from the 35 block into the upper part of the pilot-tube and issuing from the end thereof is ignited by the auxiliary flame from the small burner p. The valve B is now turned to the position of Fig. 7, whereupon gas is admitted to the 40 mixing-tube a and is ignited at the burner by the pilot-flame. As soon as the main burner is lighted the member B is turned to the position of Fig. 8, in which the supply of gas to the pilot-burners is cut off and the catalytic bodies p² are no longer subjected to the 45 injurious effect of the flame from the auxiliary pilot-burner.

For the purposes of turning the valve member B (and of course with it the main burner 50 and other parts which the said member carries) to the various positions described, devices are provided as shown in Figs. 1 and 2. Pivoted at its center to the lower part of the member B' is a lever D, to the ends of which 55 are secured operating-chains d d'. Extending upwardly from the lever at its pivot is an arm d², provided at its end with a longitudinal slot d³. Rigidly secured to the valve member B is a finger d⁴, which extends 60 through the slot d³. It will be seen that if the chain d is pulled downward the valve member B will be rotated in the direction of the arrow in Fig. 5, while if chain d' is pulled the valve member will be rotated in the op-

posite direction. Preferably the arrangement and proportions of the parts are such that pulling the chain d' down as far as it will go—that is, until the upper end of slot d³ strikes the finger d⁴—will bring the valve member B to the position of Fig. 6, and pulling chain d down until the upper end of the slot strikes the pin will restore the parts to the position of Fig. 5, while with the lever at an angle of about forty-five degrees to the horizontal the parts will be in the position of Fig. 7 and with the lever horizontal, as in Fig. 1, the parts will be in the position of Fig. 8, in which only the main or illuminating burner is supplied with gas.

From the foregoing the manner in which the device is used will be readily understood. The parts being normally in the position of Fig. 5, with the left end of lever D depressed, when it is desired to light the burner the chain d' is pulled down as far as it will go, 85 bringing the parts to the position of Fig. 6. The pilots are now ignited, whereupon the chain d is drawn down until the lever D makes an angle of about forty-five degrees to the horizontal, thus bringing the parts to the 90 position of Fig. 7, delivering gas both to the mantle-burner and the pilot-burners. The gas issuing from the mantle-burner is ignited by the main pilot-flame, which is then extinguished, as already described, by drawing the lever to the horizontal position, 95 which also brings the apertures b² and b³ into complete register.

The lighting attachment can readily be applied to any burner by removing the latter 100 from the fixture, screwing the attachment on the fixture, and then screwing the burner on the attachment. With an incandescent burner the pilot-tube is passed through a 105 suitable aperture or apertures in the chimney-gallery and seated in its support. The pilot-tube is of course made of sufficient length to reach the main burner effectively. In practice the tube may be made long 110 enough to reach the tallest burner, and then shortened when the attachment is to be applied to a shorter burner.

From the above explanation it will be seen that my invention provides a lighting attachment which can be readily applied to 115 practically any type of burner without modification thereof. At the same time the attachment is simple and not liable to get out of order and can be manufactured at comparatively small cost. The pilot-flame does 120 not burn continuously, but is ignited only when the main burner is to be lighted, and is extinguished immediately afterward, thereby avoiding waste of gas and eliminating danger of fire.

It is to be understood, of course, that the form herein illustrated and described in detail is merely the preferred form and may be 125

modified in various ways without departure from the proper scope of the invention, as defined by the appended claims.

What I claim is—

- 5 1. A self-lighting attachment for gas-burners, comprising in combination, an upwardly-tapering or conical hollow seating member adapted for attachment to a gas-pipe and provided with ports for the outflow of gas; a rotatable valve member having in its under side a tapered socket fitting the correspondingly-tapered seating member, whereby the rotatable member is supported entirely by and upon the seating member, said rotatable member being also provided with means for carrying a main burner and with a passage arranged to register with one of the ports in the seating member for supplying gas to the said main burner; and a 15 pilot-burner carried by the rotatable valve member, the valve member having an aperture in communication with the pilot-burner and adapted to register with one of the ports in the conical seating member, as set forth.
- 20 2. In a self-lighting attachment for gas-burners, the combination of a seating member adapted for attachment to a gas-pipe and provided with ports for the outflow of gas; a rotatable valve member supported entirely by and upon the seating member and provided with means for carrying a main burner, with a passage adapted to register with one of the ports in the seating member for supplying gas to the main burner, and with an aperture adapted to register with another of the ports in the seating member; a pilot-tube carried by the rotatable valve member in communication with the aperture therein and of a length to extend into proximity to 25 the main burner, the upper end of the said tube constituting a pilot-burner for lighting the main burner; an auxiliary pilot-burner below the main burner, receiving gas from the said pilot-tube; and a mass of catalytic material supported adjacent to the auxiliary pilot-burner in the path of gas issuing therefrom; as set forth.
- 30 3. In a gas-burner, the combination of a vertical tubular seating member adapted to be attached to a gas-pipe and provided with lateral ports for the outflow of gas; a valve member, fitting and rotatable on the said tubular seating member and provided with a passage and an aperture arranged to register 35 with respective lateral ports in the said seating member; a main burner carried by the

rotatable valve member and in communication with the passage therein; a pilot-burner carried by the rotatable valve member and extending into proximity to the main burner; 60 a finger extending laterally from the rotatable valve member; and a lever pivoted between its ends to the seating member below the finger thereon and provided with an upwardly-extending slotted arm engaging the 65 said finger, whereby actuation of the lever will rotate the valve member back and forth; as set forth.

4. In a self-lighting attachment for gas-burners, the combination of a vertical tubular seating member adapted for attachment to a gas-pipe and provided with two lateral ports; a valve member rotatable on and fitting the tubular seating member, having means for carrying a main burner and a 70 pilot-burner, and provided with a passage for supplying gas to the main burner and with an aperture for supplying gas to the pilot-burner, said passage and aperture being separated by a less angular distance than the 75 said ports in the seating member, whereby in one position of the rotatable valve member the gas will be cut off from the said passage and the said aperture, in another position gas will be admitted to the said aperture 80 alone, in another position to both the said passage and the said aperture, and in another to the said passage alone; and automatic means for lighting the pilot-burner when gas is supplied thereto; as set forth. 90

5. In a self-lighting attachment for gas-burners, the combination of a conical seating member B' having lateral ports b³ and b⁶; a rotatable valve member B having a tapered socket fitting the conical seating member and 95 having a threaded nipple b for carrying a main burner, and provided with a passage b², and with an aperture for supplying gas to a pilot-burner; said passage and aperture being separated by an angular distance less 100 than that between the said ports b³ and b⁶ in the seating member, whereby rotation of the valve member will bring both the said passage and the said aperture simultaneously 105 into register or out of register with their respective ports, or either into register with its respective port singly; as set forth.
